Olympia Werke West G. m. b. H., Wilhelmshaven,
Germany, a corporation of Germany

Application March 9, 1953, Serial No. 23,958

Term of patent 14 years

(Cl. D64—11)

FIG. 1

To all whom it may concern:

Be it known that I, Anton Demmel, a citizen of Germany, residing at Wilhelmshaven, Germany, have invented a new, original, and ornamental Design for a Casing for a Typewriter, of which the following is a specification, reference being had to the accompanying drawings, forming a part hereof, and wherein:

Fig. 1 is a perspective view, as seen from in front of and slightly above the same, of a casing for a typewriter showing my new design; and

Fig. 2 is a perspective view of the same as seen from the front and to the right of the typewriter.

The left side of the casing is substantially a mirror image of the right side as shown in Fig. 2 and the back of the casing is plain except for the bottom border strip.

The dominant features of the design reside in the portions shown in full lines.

I claim:

The ornamental design for a casing for a typewriter, as shown and described.
